ALF LYSHOLM, OF STOCKHOLM, SWEDEN, ASSIGNOR TO AKTIEBOLAGET LJUNGSTRÖMS
ANGTURBIN, OF STOCKHOLM, SWEDEN, A JOINT-STOCK COMPANY

BLADE SYSTEM OF GAS OR STEAM TURBINES REISSUED

Application filed June 21, 1928, Serial No. 287,176, and in Sweden June 30, 1927.

The present invention refers to certain improvements in the blade systems of gas or steam turbines, the invention having for its primary object to bring about a reduction of 5 the total number of blades required in a turbine.

A characteristic combination of features 10 of the invention is that the thickness of each blade is greater at the inlet side of the blade than at the outlet side thereof, and that the blade pitch is related to the height of the blades as $k: \sqrt{\sin \alpha}$, where $k \geq 0.5$ and < 1.5 and α designates the outlet angle of the blade.

A further characteristic combination of 15 features according to the invention is that the maximum thickness of each blade is on the inlet side of the line of gravity of the blade and thence decreases toward the outlet side, and that the blade pitch is related to 20 the height of the blades as $k: \sqrt{\sin \alpha}$, where $k \geq 0.5$ and < 1.5 and α designates the outlet angle of the blade.

A further characteristic combination of 25 features is that each blade has a rounded shape toward the incoming steam, and that the blade pitch is related to the height of the blades as $k: \sqrt{\sin \alpha}$, where $k \geq 0.5$ and < 1.5 and α designates the outlet angle of the blade.

A further characteristic combination of 30 features is that the thickness of each blade is greater at the inlet side of the blade than at the outlet side thereof, and that the blade pitch is 0.9 to 1.5 times the dimension of the blades, measured in the direction of flow of 35 the driving fluid.

A further characteristic combination of 40 features is that the maximum thickness of each blade is on the inlet side of the line of gravity of the blade and thence decreases toward the outlet side, and that the blade pitch is 0.9 to 1.5 times the dimension of the blades, measured in the direction of flow of the driving fluid.

A further characteristic combination of 45 features is that each blade has a rounded shape toward the incoming driving fluid, and that the blade pitch is 0.9 to 1.5 times the dimension of the blades, measured in the direction of flow of the driving fluid.

50 The feature of providing rounded inlet

edges in the blades of elastic fluid turbines, and of thus imparting to the blades a streamline contour to increase the efficiency of the individual blades, is known to be previously suggested in the art of turbine design, whereas the combined features of rounding the inlet edges of the blades or of locating the maximum thickness of each individual blade to the inlet side of the blade, and of providing a blade pitch which is related to the height of the blades as $k: \sqrt{\sin \alpha}$, where $k \geq 0.5$ and < 1.5 and α designates the outlet angle of the blade, or which is 0.9 to 1.5 times the height of the blades, are novel and characteristic of my present invention, to the best of my knowledge and belief.

In the accompanying drawings, Fig. 1 represents a cross-section of one of the blades of the improved blade system according to the invention. Figs. 2 and 3 show a few blades of the type considered in connection with the present invention and spaced as they will be in a blade system according to the invention.

With reference to Fig. 1 of the drawings, A denotes the center of gravity of the blade, while B is the center line of the blade. This center line is divided into three equal parts, and through the dividing points intersecting lines C and D are drawn at right angles to the center line. E is the height of the blade, that is to say, its dimension measured in the direction of flow of the driving fluid, this direction being an axial one in an axial-flow turbine and a radial one in a radial-flow turbine. α designates the outlet angle of the blade.

As will be clearly seen, the greatest thickness of the blade is on the inlet side of the blade, the said thickness being located in front of the center of gravity A. The mass of the blade is so distributed with respect to the outlet angle α that the most suitable blade pitch of the turbine, that is to say, the most suitable distance between the blades, with respect to the height of the blades, will be obtained if the pitch is related to the height of the blades as $k: \sqrt{\sin \alpha}$ where $k \geq 0.5$ and < 1.5 .

It will be found that the above law provides for blade pitches equal to or approximately equal to the dimension of the blades

measured in the direction of flow of the fluid, the same being between the limits 0.9 to 1.5 times the said dimension, whereas in the blade systems as hitherto devised the blade pitch is only about 0.7 times the dimension of the blade, measured in the direction of flow of the fluid. Consequently, the advantage is gained through the present invention that a smaller number of blades are required in the whole turbine than hitherto, the possible reduction of the number of blades being, in fact, 20 to 40%, involving a corresponding reduction in the cost of manufacture.

In Fig. 2, which illustrates a blade system according to the invention where the thickness of each blade is greater at the inlet side of the blade than at the outlet side thereof, a path of the driving fluid between the blades is indicated by lines *g*.

Fig. 3 shows how the fluid, the path of which is indicated by the lines *h*, *h*, passes the same blades as those shown in Fig. 2, but under a different relative inlet angle. On account of the increasing width and rounding of the blade section toward the incoming steam, eddies which arise in previously known blade systems on account of variations in the direction and velocity of the incoming steam jet are not produced. It has been shown by trials that the incoming steam may vary materially both with respect to velocity and direction, without the efficiency of the blade system being appreciably impaired thereby.

As illustrated, the blades of a blade system according to the invention are given a greater thickness at the inlet side than at the outlet side, and the edge of the blade directed toward the entering steam is rounded on the lines of a circle, ellipse, parabola or hyperbola, or has an approximately similar shape.

By thus adopting blades of the shape disclosed in Figs. 1, 2 and 3 for the blade system according to the present invention, the further advantage is gained, in addition to that of a reduced blade pitch, that the losses will be comparatively independent of the direction of the incoming steam jet. Therefore, the efficiency of the blade system will be independent of the variations and speed conditions involved by overloading, reduced loading or a variable number of revolutions of the turbine. Moreover, when steam is used as a driving fluid, such blade systems are suitable in localities where the percentage of moisture of the steam is high, inasmuch as they offer, in the first place, greater resistance to wear and, furthermore, are suited to the altered inlet angles under which the moisture of the steam is supplied to the blade system.

Inasmuch as the novel blade systems are to a greater extent independent of the inlet angle of the fluid, it is no longer necessary, as

is the case in certain turbines, that blades are made in different sizes, for instance with a radial dimension of 5, 7 and 10 millimeters, and that each dimension is made in 10 different blade profiles suited to different inlet and outlet angles, or, altogether, about 30 different blade profiles. Blade systems according to the invention may be built with blades of a single size having a dimension of 10 millimeters in the direction of flow of the fluid, and only 2 or 3 blade profiles are required for different directions and velocities of the fluid. In the standardization of turbine manufacture with blade systems according to the invention it will thus only be necessary to make $\frac{1}{10}$ of the number of blade types that has been previously required.

On account of the above it may be of advantage, economically, to provide blades milled in their entirety and inserted directly into the ring bonds uniting the blades in the blade rings, it being then also possible to make the outer blade lengths at least 20% longer, whereby the output of the turbine may be increased in a corresponding degree, or, if the same blade length is employed, while the height of the blade is reduced, the sum of the squares of the speeds may be increased. In order to obtain a turbine, for example a back pressure turbine with possibilities of overloading by means of by-passage while maintaining a good efficiency under all conditions, the relation of velocity $\frac{v}{c}$ should be great. With a blade system according to the invention, this relation $\frac{v}{c}$ may be increased to values >0.8 , without the thin blades of earlier constructions being obtained. Moreover, a turbine constructed with a blade system according to the invention will obtain an increased turning moment at the moment of starting, and for this reason such a turbine can better be used, for instance as a motor for the driving of locomotives, whereby the capability of the locomotive to force gradients is increased.

What I claim as new and desire to secure by Letters Patent of the United States of America is:—

1. In a blade system for gas or steam turbines, the combination of the features that the thickness of each blade is greater at the inlet side of the blade than at the outlet side thereof, and that the blade pitch is related to the height of the blades as $k:\sqrt{\sin \alpha}$, where $k \leq 0.5$ and <1.5 and α designates the outlet angle of the blade.

2. In a blade system for gas or steam turbines, the combination of the features that the maximum thickness of each blade is on the inlet side of the line of gravity of the blade and thence decreases toward the outlet side, and that the blade pitch is related to the height of the blades as $k:\sqrt{\sin \alpha}$, where

$k \leq 0.5$ and < 1.5 and α designates the outlet angle of the blade.

3. In a blade system for gas or steam turbines, the combination of the features that each blade has a rounded shape toward the incoming steam, and that the blade pitch is related to the height of the blades as $k: \sqrt{\sin \alpha}$, where $k \leq 0.5$ and < 1.5 and α designates the outlet angle of the blade.

10 4. In a blade system for gas or steam turbines, the combination of the features that the thickness of each blade is greater at the inlet side of the blade than at the outlet side thereof, and that the blade pitch is 0.9 to 1.2 times the height of the blades.

15 5. In a blade system for gas or steam turbines, the combination of the features that the maximum thickness of each blade is on the inlet side of the line of gravity of the blade and thence decreases toward the outlet side, and that the blade pitch is 0.9 to 1.2 times the height of the blades.

20 6. In a blade system for gas or steam turbines, the combination of the features that each blade has a rounded shape toward the incoming driving fluid, and that the blade pitch is 0.9 to 1.2 times the height of the blades.

25 7. In a blade system for gas or steam turbines, the combination of the features that the inlet edge of each blade is of a circular cross-section, and that the blade pitch is related to the height of the blades as $k: \sqrt{\sin \alpha}$, where $k \leq 0.5$ and < 1.5 and α designates the

30 outlet angle of the blade.

8. In a blade system for gas or steam turbines, the combination of the features that the inlet edge of each blade is of a circular cross-section, and that the blade pitch is 0.9 to 1.2 times the height of the blades.

35 9. In a blade system for gas or steam turbines, the combination of the features that the maximum thickness of each blade is on the inlet side of the line of gravity of the blade and thence decreases toward the outlet side, and that the blade pitch is $> .9$ and < 1.5 times the height of the blades.

In testimony whereof I affix my signature.
ALF LYSHOLM.
